P. R. SYERS.
LAUNDRY BAG HOLDER.
APPLICATION FILED DEC. 13, 1921.

1,424,690.

Patented Aug. 1, 1922.

INVENTOR.
PAUL R. SYERS.

BY
E. Bradford
ATTORNEY.

UNITED STATES PATENT OFFICE.

PAUL R. SYERS, OF INDIANAPOLIS, INDIANA.

LAUNDRY-BAG HOLDER.

1,424,690.

Specification of Letters Patent. Patented Aug. 1, 1922.

Application filed December 13, 1921. Serial No. 522,067.

To all whom it may concern:

Be it known that I, PAUL R. SYERS, a citizen of the United States, residing at Indianapolis, in the county of Marion and State of Indiana, have invented certain new and useful Improvements in Laundry-Bag Holders, of which the following is a specification.

This invention relates primarily to laundry bag holders, but it will be understood that the device may be used for holding various kinds of bags. The prime feature of the invention is the provision, in connection with stationary supports, of gravity operated supports for opening and maintaining the mouth of the bag in open position and at the same time supporting the bag so that articles may be readily placed therein.

A further feature of the invention is the provision of a platform in connection with the gravity operated parts upon which the bag rests, said platform being so arranged that the added weight of the articles placed within the bag will increase the tension around the mouth of the bag and retain the same in open position.

A further feature of the invention is the provision of means for reinforcing parts of the device.

A further feature of the invention is the provision of a base which is preferably mounted upon castors or rollers whereby the bag holder may be readily transported from place to place.

Other objects and advantages will be hereinafter more fully set forth and pointed out in the accompanying specification.

In the accompanying drawings,

Figure 1 is a perspective view of the bag holder in operative position showing a bag thereon in dotted lines,

Figure 2 is a side elevation of the bag holder showing in full lines the position of the parts before a bag is attached thereto, and the position of the movable parts by dotted lines when said parts have swung to operative position,

Figure 3 is an edge elevation of the device, Figure 4 is a top plan view thereof, and

Figure 5 is a side elevation of a modified form of structure.

Referring to the drawings, 1 indicates a base which is in the form of a frame, preferably rectangular in shape and mounted

upon casters or rollers 2, so that the base 55 may be readily transported from place to place. In order to suspend a bag above the base and hold the mouth portion thereof open so that articles can be readily introduced into the bag, a pair of standards 3 60 are secured in any suitable manner to the base 1 adjacent one end thereof, the lower ends of the standards preferably passing within the base and engaging the inner faces of the sides and one end bar of the base, so 65 as to lend rigidity to the standards, and if desired the upper ends of said standards may be reinforced and secured together by means of a cross bar 4. Pivoted to the standards 3 adjacent their lower ends by 70 means of a pivot bolt 6, is one end of a platform 5, and to the opposite end of said platform are connected a pair of standards 7, the standards 7 being positioned some distance from the pivot point of the platform 75 so that they will have gravity action and will normally tend to swing downwardly, the upper ends of the standards being preferably connected by a cross bar 8, and if preferred, brace arms 9 may be extended 80 from parts of the platform to the standards 7 for bracing the same. The platform 5 is of less length than the base 1, so that the end of the platform containing the standards 7 may readily swing downwardly between the 85 side members of the base.

In Figure 5 of the drawings, the standards 10 connected with the platform, are passed exteriorly of the standards 3 and are connected with that end of the platform 90 pivoted to the standards 3 and are extended at an angle so that the upper ends thereof will assume approximately the same position as the upper ends of the standards 7, the operation thereof being substantially identical. 95 In this form of device, however, the cross bar at the upper ends of the standards 10 is dispensed with so that the bag may be readily moved outwardly from between the standards 10.

This device is designed primarily for use in laundries, although it will be clearly understood that it may be used for holding various kinds of bags.

In applying the device to use, the bag is 105 placed on the platform and the standards 7 moved to the position shown by full lines in Figure 2. The mouth portion of the bag

is then folded outwardly and downwardly to form a cuff or pocket for engagement with the ends of the standards 3 and 7, the bottom of the bag resting upon the platform 5. 5 The standards 7 are then released, whereupon they will swing outwardly and downwardly by gravity and draw the mouth of the bag taut and hold the same open so that articles may be readily introduced into or 10 removed from the bag. As soon as the bag has been filled the folded portion thereof is released from the ends of the standards when the bag and its contents may be readily removed from the platform. 15 This device may be very cheaply manufactured and at the same time rendered strong and durable, and by mounting the base portion on castors or rollers it may be moved from place to place, as occasion may 20 require. It will likewise be seen that the bag may be easily and quickly attached to the holder or removed therefrom, and that the mouth of the bag will be held in open position at all times as the weight of the articles placed within the bag will increase the 25 pull of the standards 7 against the mouth of the bag, thereby increasing the tension of the bag at its open end as it is gradually filled. However, but a slight lifting action 30 on the standards 7 is required to instantly release the folded over portion of the bag from the standards.

Having thus fully described my said invention, what I claim as new and desire to secure by Letters Patent, is:

35 1. In a bag holder, a pair of fixed standards, a platform pivotally connected with said standards and adapted to swing downwardly by gravity, and standards connected

with said platform and co-acting with the 40 fixed standards for engaging and maintaining the mouth of a bag in open position.

2. In a bag holder, a base, standards fixed to said base, a platform pivoted adjacent one end of said standards, and additional standards carried by said platform and adapted to swing by gravity for moving the upper ends thereof away from the upper ends of the fixed standards, said upper ends of said standards holding a bag in open and suspended position. 45 50

3. In a bag holder, a base member, standards fixed to said base member, a platform pivoted to said standards, additional standards carried by the platform, the upper ends 55 of which are adapted to swing towards or from the fixed standards when the platform is titled, and means for bracing said standards.

4. In a bag holder, fixed standards, a tilting platform associated therewith, and additional standards carried by and adapted to swing with said platform the upper ends of said swinging standards and the upper ends 60 of said stationary standards being in spaced 65 relation whereby when a bag is engaged therewith said pairs of standards will serve to support the bag and maintain the mouth thereof in open position.

In witness whereof, I have hereunto set 70 my hand and seal at Indianapolis, Indiana, this 5th day of December A. D. nineteen hundred and twenty-one.

PAUL R. SYERS. [L. S.]
